CLAY WORKING MACHINE

Russell T. Voris, Dayton, Ohio, assignor to The Manufacturers Equipment Company, Dayton, Ohio, a corporation of Ohio

Application November 4, 1933, Serial No. 696,645

19 Claims. (Cl. 25—109)

This invention relates to clay working machines and is designed more particularly for use with a brick making machine having a plurality of cutters for severing a column of clay into brick size sections. In a machine of this character the clay is usually forced through a die to form the same into a column of the desired cross sectional shape and this column is delivered to the cutting mechanism which severs successive portions of the same into sections. It is frequently desirable to impart to one surface of the severed section a configuration different from that which can be imparted thereto by the die. For example, certain types of paving brick are provided on one vertical surface with a plurality of lugs arranged in definite relation thereto. Further, it is often desirable that the severed sections should have smooth even upper edges and the cutting mechanisms as commonly employed are very apt to leave these upper edges more or less uneven and fuzzy. It has been proposed heretofore to associate with such cutting mechanism an apparatus comprising pressure plates shaped to impart the desired configuration to one surface of the severed section and/or to cooperate with the cutters to provide a clean cut which will leave the upper edges of the severed sections smooth and even. Such an apparatus is shown in the application filed by Karl R. Forry on November 1, 1933 Serial No. 696,172, and owned by the assignee of the present application, and the present invention is in the nature of an improvement upon the apparatus there shown.

One object of the present invention is to provide such an apparatus with actuating mechanism for the pressure plates which will be simple in construction and inexpensive to construct.

A further object of the invention is to provide such an apparatus in which the actuating mechanism for each pressure plate will be complete in itself and will be wholly mechanical in its operation.

A further object of the invention is to provide such an apparatus with individual actuating mechanisms for the respective pressure plates which will be operated by the cutting mechanism itself.

Other objects of the invention will appear as the apparatus is described in detail.

In the accompanying drawings Fig. 1 is a front elevation, partly broken away, of a portion of a brick making machine embodying my invention; Fig. 2 is an end elevation of the cutting mechanism of such a machine; Fig. 3 is a transverse sectional view of the cutting mechanism; Fig. 4

is a detail view, partly in section, showing a part of the pressure devices and their operating mechanism; Fig. 5 is a bottom plan view of one of the pressure plates; and Fig. 6 is a detail view of one of the severed sections.

In these drawings I have illustrated one embodiment of my invention and have shown the same in connection with a brick making machine of a well known type. It will be understood, however, that the invention may take various forms and may be associated with various types of machines designed for severing columns of plastic material into sections.

In the particular machine here illustrated the clay is forced in the usual manner through a die, a portion of which is shown at 10, and which forms the clay into a continuous column having the desired cross sectional shape. This column of clay is received from the die by a conveyor 11 which delivers the same to the cutting mechanism. The cutting mechanism as a whole is mounted on a supplemental base or frame 12 and is capable of a reciprocatory movement in the direction of the length of the clay column, for a purpose which will hereinafter appear. The supplemental device 12 is therefore provided with downwardly facing track sections 13 which rest upon rollers 14 which in turn are mounted to travel on short track sections 15 carried by a main base 16 which forms part of the main supporting structure for the mechanism. Rigidly mounted on the supplemental base 12 and spaced one from the other are upright frame members 17 which are rigidly connected one to the other by a longitudinal center structure 18, sometimes called a center column. Each frame member comprises a plurality of arms 19 extending substantially radially from the center structure and each of these arms has at its outer end a roller 20. Mounted for rotation about the center structure 18 is a cutter reel which comprises two gears 21 having external gear teeth and internal track portions which are supported on and travel about rollers 20 of the respective end frames 17. These gears are rigidly connected one to the other by a plurality of tie bars 22, there being in the present instance four of these tie bars each of which is formed of angle iron. The cutters are in the form of wires 23 arranged radially of the cutter reel and connected at their outer ends with the bars 22, preferably through the medium of relatively stiff springs 24, and connected at their inner ends with rotatable members or brackets 25 rotatably mounted on the center structure. There are, in the present instance, four series

of wires 23 spaced equal distances apart about the reel and the wires of each series are spaced one from the other a distance equal to the width of the sections which are to be severed. The corresponding cutting wires of each series are connected with the same supporting bracket 25 so that the corresponding cutting wires in the several series will lie in the same vertical planes and therefore travel in the same paths.

10 Mounted within the cutter reel are a plurality of supporting devices arranged to receive and support that portion of the clay column which is to be severed into sections and these supporting devices are spaced one from the other to permit the respective cutting wires to pass between the same when rotatory movement is imparted to the reel. As here shown, each supporting device is in the form of a bracket 26 rigidly secured to and depending from the center structure and is provided with a bottom plate 27 and a back plate 28 to engage the bottom and rear surface of the clay column and hold the same against lateral displacement during the cutting operation.

15 Intermittent rotatory movement is imparted to the cutter reel by pinions 29 which mesh with the respective gears 21 and are secured to a shaft 30 mounted in front of the reel and journaled in bearings 31 carried by brackets 32 mounted on the supplemental base 12. Rotatably and slidably 20 mounted on the shaft 30 is a drum 33 having rigidly secured to one end thereof a clutch member 34 arranged to cooperate with a second clutch member 35 mounted on the shaft 30 and held against rotation with relation thereto. The 25 clutch member 34 is pressed normally into engagement with the clutch member 35 by a spring 36 mounted in the drum 33. Wound about the drum 33 and connected therewith is a chain 37 which extends downwardly about a guide sheave 38 and thence upwardly and is connected with a crank pin 39 on a driving gear 40 mounted on the shaft 41. This gear is driven by a pinion 42 which is connected by a train of gears 43 with a belt wheel 44. A second chain 45 is also connected with the drum 33 and extends upwardly therefrom and is connected with one end of a counterbalancing lever 46 pivotally mounted on a suspended fulcrum 47 and having its other end counterweighted, as shown at 48. The driving 50 gear 40 is rotated continuously and the gear and its cooperating mechanism are so arranged that at the beginning of each operation of the cutting mechanism the crank pin will be at or near its lowest position. As the crank pin moves upwardly the chain 37 is unwound from the drum 33 and thus rotates that drum; and, through the medium of the clutch members 34 and 35 imparts rotatory movement to the pinions 29 and the cutter reel, the gear ratio being such that a half 55 rotation of the driving gear 40 will impart a quarter rotation to the reel. When the crank pin 39 passes its uppermost position and moves downwardly the chain 37 will be slackened off and the chain 45, which has been wound onto the drum 33 by the unwinding of the chain 37, will then be unwound from the drum 33 by the action of the counterweight and the drum and the clutch member 34 will be rotated in a reverse direction, thus causing the clutch member 34 to ride over the 60 teeth of the clutch member 35, thereby restoring the clutch members to their initial position without imparting reverse movement to the cutter reel. The cutting wires are so arranged on the reel that each quarter rotation will carry one 65 set of wires through the clay column and the

reel will come to a stop with that set of wires positioned slightly beyond the column. Inasmuch as the clay column moves continuously means are provided for moving the cutting mechanism forwardly during the cutting operation at the same speed at which the clay column is moving, thereby causing the wires to sever the column along lines at right angles to the column. At the end of this cutting operation and while the reel is held against rotation the cutting mechanism as a whole is restored to its initial position. The means for imparting this reciprocatory movement to the cutting mechanism is not involved in the present invention and therefore need not be illustrated or described in detail. The clay column travels forwardly during the cutting operation and during the rearward movement of the cutting mechanism and by the time the cutting mechanism reaches its rearmost position another portion of the clay column will be in engagement with the several supporting devices and ready for the next cutting operation. The continuous movement of the clay column forces the severed sections off of the supporting devices and onto a delivery conveyor 49 which preferably moves at a speed slightly greater than the speed of the clay column so as to separate the several sections and facilitate their removal.

100 The mechanism here shown is designed for forming paving bricks 50 each having on one vertical surface two pairs of lugs 51, the lugs of each pair being spaced one from the other and from the upper and lower edges of the vertical surface. The cross-sectional shape of the clay column conforms to the top and bottom surfaces of the paving brick, these surfaces being formed by the severed edges of the sections. Consequently the upper surface of the clay column forms one of the vertical surfaces of the brick and the brick is shown in Fig. 6 in the position which it occupies during the severing and forming operations. In order to form the lugs on the severed sections the die itself is shaped to provide the upper surface of the clay column with two continuous ribs, one of which is shown at 52 in Fig. 1, these ribs being arranged in the position which the lugs 51 are to occupy. In order to convert these continuous ribs into lugs there is mounted above each supporting device 26 a pressure plate 53 which may be moved into engagement with the corresponding section of the clay column before or during the severing operation. The lower surface of this plate is shaped to impart the desired configuration to the upper surface of the section and, in the present instance, it is provided with two pairs of recesses 54 arranged in the positions which are to be occupied by the lugs. When the pressure plate is pressed into engagement with the section those portions of the plate which lie between and on the outer sides of the recesses will press the adjacent portions of the rib 51 into the body of the section, the remaining portions of the rib entering the recesses, which impart thereto the desired shape. The edges of adjacent pressure plates 53 are preferably spaced apart a distance substantially equal to the thickness of the cutting wires so that they will cooperate with those cutting wires, in the manner of cutter bars, to provide a clean sharp cut along the upper edge of the section.

105 Any suitable mechanism may be provided to actuate the pressure plates 53 in properly timed relation to the successive movements of the cutter reel and I have here shown individual actuating mechanisms for the several pressure plates which are wholly mechanical in their operation,

as distinguished from the fluid pressure operated devices of the above mentioned application. I also prefer that the actuating devices shall be of such a character that they may be simultaneously operated by the reel itself, thereby insuring the operation of the pressure plates at the desired time with relation to the movements of the reel. As here shown each pressure plate is secured to and supported by a rod or plunger 55 50 slidably mounted in a bracket 56 rigidly secured to the center structure 18 and arranged between the paths of travel of adjacent cutting wires. The pressure plate is held against rotary movement about the axis of the plunger 55 by means of a pin 57 secured thereto and also guided in the bracket 56. The plunger 55 has at its upper end pivot lugs 58 to which is pivotally connected one end of a lever 59, the other end of which is pivotally mounted at 60 on an upright plate or bracket 61 also rigidly secured to the center structure 18, the lever preferably extending across the center structure and the axis 16 being arranged on that side of the center structure opposite the plunger 55. The pressure plate 25 is moved to its uppermost position and retained in that position by a spring 62 confined between the bracket 56 and the pivot lugs 58. A cam 63 is pivotally mounted on the bracket 61 above the lever 59 and is arranged to act on that lever to force the same downwardly against the action of the spring 62, the lever preferably being provided with a roller 64 with which the cam engages. Rigidly secured to the cam is an arm 65 which is arranged to be engaged by a part of the reel and actuated to cause the cam to depress the pressure device. A spring 66 is connected with the arm 65 to restore the same to its normal position and thus release the pressure plate for upward movement when the arm has been released by the reel. 30 When the pressure plate is used for embossing purposes only the cam may be actuated to press the plate into engagement with the clay section either before the cutters engage the clay column or during the cutting operation but when the pressure plate is to cooperate with the wires to provide a clean cut edge on the section the pressure plate should be pressed into engagement with the clay column before the latter is engaged by the cutting wires and should be retained in engagement with the column during the entire cutting operation and, in the form illustrated, the actuating mechanism is arranged and timed to provide for this latter operation. As here shown, the cam actuating arm 65 is supported normally in a substantially vertical position, as shown in dotted lines in Fig. 3, in which position the cam will have released the pressure plate and the latter will have been moved to its elevated position. When the arm 65 is in its normal or upright position the upper end thereof lies in the path of the tie bars 22 of the reel. The movements of the cutter reel are so timed that at the end of each cutting operation the reel will stop with the wires which have performed the cut located just beyond the rear edges of the sections, in an almost vertical position. This results in the succeeding series of wires, which are to perform the next cutting operation, being located in approximately horizontal positions and spaced a substantial distance from the clay column. The arrangement also results in the uppermost tie bar 22 being located in the rear of but close to the upright cam actuating arm 65, as shown in dotted lines in Fig. 3. When rotatory movement 35 is again imparted to the reel this uppermost tie bar will engage the cam arm and rock the cam about its axis and thus cause the pressure plate to be pressed into engagement with the clay column. The succeeding set of cutter wires being spaced a substantial distance from the clay column there is ample time within which the cam may actuate the pressure plate before the cutting wires engage the clay column. As the cutter reel continues its rotation the tie bar will ride over the end of the cam actuating arm and will, prior to the completion of the quarter rotation of the reel, release the arm so that it may be returned to its normal position by the spring 66. When, as in the present instance, the pressure plate is to be retained in engagement with the clay column throughout the cutting operation the tie bars 22 may be provided with rear extensions 67 which will hold the arm 65 in its depressed position until the reel has almost completed its quarter rotation and will then release the same. 40 The operation of the apparatus will be readily understood from the foregoing description and it will be apparent that I have provided very simple but highly efficient actuating mechanisms for the pressure plates and that the separate actuating mechanisms for the respective pressure plates are so arranged that they will in no way interfere with the operation of the cutting mechanism but will be engaged and positively actuated by a part of the cutter reel, thereby 45 enabling the operation of the pressure plates to be accurately timed with relation to the movements of the reel and also enabling the pressure plates to be retained in engagement with the clay sections for any desired length of time. 50 While I have shown and described one embodiment of my invention I wish it to be understood that I do not desire to be limited to the details thereof as various modifications may occur to a person skilled in the art. 55 Having now fully described my invention, what I claim as new and desire to secure by Letters Patent, is:

1. In a machine for severing a column of plastic material into sections comprising a cutter and means to support the section to be severed during the severing operation; a device mounted adjacent to said supporting means for movement into engagement with a section of material which is in severing position thereon, and means actuated by a moving part of said machine for moving said device into engagement with said section of material. 60
2. In a machine for severing a column of plastic material into sections comprising cutting mechanism and means to support the section to be severed during the severing operation; a device mounted adjacent to said supporting means for movement into engagement with a section of material which is in severing position thereon, and means actuated by said cutting mechanism for moving said device into engagement with said section of material. 65
3. In a machine for severing a column of plastic material into sections comprising a cutter and means to support the section to be severed during the severing operation; a device mounted adjacent to said supporting means for movement into engagement with a section of material which is in severing position thereon, cam operated means for pressing said device into engagement with said section of material, and means for controlling the movements of said cam in accordance with the movements of said cutter. 70
